DESIGN FOR AN ATOMIZER

Carsten F. Boe, Wilmington, Del.

Application August 2, 1945, Serial No. 121,178

Term of patent 14 years

(Cl. D83—1)

To all whom it may concern:

Be it known that I, Carsten F. Boe, a subject of the King of Norway, having declared his intentions of becoming a citizen of the United States, residing in Wilmington, New Castle County, Delaware, have invented a new, original, and ornamental Design for an Atomizer, of which the following is a specification, reference being had to the accompanying drawing, forming a part thereof.

Fig. 1 is a perspective view of an atomizer showing my new design;

Fig. 2 is a top plan view thereof; and

Fig. 3 is a side elevation thereof.

I claim:

The ornamental design for an atomizer, as shown.

CARSTEN F. BOE.
